DRILL BIT

Jacob E. Feucht, Garfield Heights, Ohio, assignor to Westinghouse Air Brake Company, Wilmerding, Pa., a corporation of Pennsylvania

Filed Jan. 27, 1958, Ser. No. 711,517

4 Claims. (Cl. 255—64)

This invention relates generally to drills and more particularly to a drill bit and drill steel, and the connection therebetween, of the type in which the bit is slipped over the tapered end of the steel to form a wedge fit therewith.

In conventional drills of this general type the drill steel frequently broke on its connecting portion. When this occurs, the drill steel must not only be reconditioned, but the hole which was being drilled may be lost. Furthermore, the bits themselves frequently break by the wedging action of the drill rod, when the latter is driven by the pneumatic drill to which it is attached.

A tight wedging fit is required between the drill rod and bit in order to form a seal therebetween which insures that cleansing fluid is ported from the center of the drill rod through the holes in the bit.

In accordance with the present invention an improved bit and steel connection is provided which prevents stress concentration in the connection portion of the drill steel and in the bit and consequent breakage thereof.

More particularly, the tapered skirt of the bit extends beyond the complementary tapered surface of the rod and around a portion of the rod that is non-circular in cross section. Thus the stresses set up primarily in the connection portion of the drill steel are distributed and thereby prevented from being concentrated in any one section.

In addition, the invention further contemplates that the skirt portion of the bit is made of more ductile steel than the cutting edges thereof and the skirt may deform slightly over the non-circular portion of the rod. This deformation not only contributes to reduce stresses at the connection point but also prevents the bit from rotating on the drill.

A drill bit and rod have been provided in which a sealing press fit is formed therebetween and which further distribute stresses in the bit at its connection point so as to prevent breakage thereof.

These and other objects and advantages will appear hereinafter as this disclosure progresses, reference being had to the accompanying drawings, in which:

Figure 1 is a side view of a drill bit and rod made in accordance with the invention, the bit being in section, and the view being taken along line 1—1 of Figure 3;

Figure 2 is a view similar to Figure 1, but on an enlarged scale and showing both the bit and rod in section, the view being taken on line 2—2 of Figure 3;

Figure 3 is a sectional view, on an enlarged scale, taken on line 3—3 of Figure 1 and showing the deformation of the bit skirt from its original broken line position; and

Figure 4 is a cross-sectional view, on an enlarged scale, taken on line 4—4 of Figure 1.

Referring in greater detail to the drawings, the drill rod 6, or drill steel as it is commonly referred to, is generally of non-circular cross-sectional shape. For purposes of illustration the rod has been shown as being of hexagonal cross-section, but other non-circular shaped

2

cross-sections may be employed with the present invention. The end of the rod 6 is tapered to form a conical portion 7 which terminates in a flat end 8. The drill steel 6 is of greater cross-sectional area than conventional steels, at the initial point of contact with 5 the bit which has contributed to increased strength and life of the steel.

An irregular breakout line 9 is formed at the juncture of the conical section 7 and hex section.

Various types of bits may be utilized with the present invention and the bit 10 chosen for illustration is of 10 the type having four integral cutting edges 11.

The bit includes a skirt 12 which defines a tapered socket 13 that terminates in the bottom 14. The tapered socket is complementary to the tapered portion 15 of the rod and forms a leakproof joint that assures the passing of cleansing fluid from the bore 15 of the rod out through the holes 16 in the drill bit. It is preferable to prevent the end of the drill steel 8 from bottoming in the bit. It will be noted that the conical portion 7 of the rod wedges tightly in the bit skirt and therefore does not usually contact the bit bottom 14. This construction provides full circumferential contact and assures that the bit will stay tight on the rod and usually will not be driven thereon to a point where the rod bottoms in the socket, thus allowing a wide tolerance of dimensions between the socket and rod.

As shown in Figure 2, the end portion 18 of the skirt extends beyond the conical portion 7 of the rod and 20 extends around the hex portion thereof, leaving a space 30 19 between the hex flats and the skirt.

As the bit is driven onto the rod, the irregular breakout line 9 distributes any stresses in the drill steel and 35 prevents stress concentration therein. In other words, if the irregular breakout line was not provided and instead the tapered portion of the steel was of full circular cross-section throughout the length of the skirt 12, then when the bit was in use, a line of stress would be developed transversely across the steel to cause fracture along this 40 transverse line. However, by providing an irregular breakout line which is formed at the juncture of the conical portion and the hex portion, these stresses are distributed along that length of the steel within the skirt and are not concentrated in any one transverse 45 plane across the steel. The contact section of the skirt contacts the drill steel at the irregular breakout line and distributes the stresses. Only a relatively small conical section of the steel engages the bottom portion of the socket of the bit to give full circular contact, thus providing a leak-proof joint and assuring cleansing fluid 50 being ported into the bit holes. The bit life will also be increased although the bit is a more expendable item. Experience with these improved drill steels and bit connections has shown a marked reduction in the 55 breakage of these steels and bits that occurred in prior art devices where full circumferential contact for the axial length of the skirt on the rod was provided.

In the manufacture of bits made in accordance with this invention, a straight .60 to .90 carbon steel has 60 proved very satisfactory. The bit is heat treated by heating it to approximately 1400 degrees F. and then quenching only the cutting edges to a depth of about one-quarter of an inch. When quenched in a brine solution in this manner, the edges are hardened to 62-65 Rockwell C. The balance of the bit becomes progressively softer towards the other end. The other end of the bit, that is the annular skirt portion 18, is left soft, at about a Rockwell C of 20, which is a ductile condition that can be deformed and stretched without breaking.

As shown in Figure 3, when a bit made in accordance

with the above procedure is driven on the rod, the outer edge 18 of the skirt is deformed to partially follow the shape of the non-circular cross-section part of the rod. The broken line indicates the original circular shape of the skirt before deformation. Due to the partial deformation of the skirt to the hex shape, the skirt is prevented from rotating on the drill rod and a particularly tight connection results between the bit and rod. By means of this invention, relatively easy manufacturing tolerances are permissible between the parts; breakage of the drill rod connections and the bits has been substantially eliminated; and a fluid tight seal is provided to assure proper flushing of spoil at the bit.

Various modes of carrying out the invention are contemplated as being within the scope of the following claims particularly pointing out and distinctly claiming the subject matter which is regarded as the invention.

I claim:

1. In combination, a drill rod having a portion of its length of non-circular cross-section, said rod also having a tapered end forming a conical portion, said conical and breakout line, a drill bit having a skirt portion which defines a tapered socket which extends to terminate at the skirt end, said tapered socket being complementary to said conical portion and forming a sealing fit therewith, said skirt extending over at least part of both said non-circular portion and breakout line and said skirt end is spaced from said non-circular portion whereby stress concentration is minimized due to stress distribution along said breakout line.

2. In combination, a drill rod having a portion of its length of non-circular cross-section, said rod also having a tapered end forming a conical portion, said conical and non-circular portions merging to form an irregular breakout line, said rod also having a cleansing fluid bore extending axially therethrough, a drill bit having a skirt portion which defines a tapered socket which extends to terminate at the skirt end, said tapered socket being complementary to said conical portion and forming a sealing fit therewith, said bit having an aperture extending therethrough for conducting cleansing fluid from said bore through said bit, said skirt extending over at least part of both said non-circular portion and breakout line and being spaced from the former whereby stress concentration is minimized.

3. In combination, a drill rod having a portion of its length of non-circular cross-section, said rod also having a tapered end forming a conical portion, said conical and non-circular portions merging to form an irregular breakout line, a drill bit having an annular skirt portion which defines a tapered socket which extends to terminate at the skirt end, said tapered socket being complementary to said conical portion and forming a sealing fit therewith, said skirt extending over at least part of both said non-circular portion and breakout line and being spaced from the former whereby stress concentration is minimized, said skirt portion being sufficiently ductile so as to deform over said non-circular portion without fracture.
4. In combination, a tubular drill rod having a portion of its length of non-circular cross-section, said rod also having a tapered end forming a conical portion, said conical and non-circular portions merging to form an irregular breakout line, a drill bit having hardened cutting teeth at one end and a skirt portion at the opposite end which defines a tapered socket extending therefrom and terminates at the skirt end, said tapered socket being complementary to said conical portion and forming a sealing fit therewith, said bit having an aperture for conducting fluid from said rod through said bit, said skirt having an end portion extending over at least part of both said non-circular portion and breakout line and being spaced from the former whereby stress concentration in said rod is minimized, said end portion being sufficiently ductile to deform around said non-circular portion without fracture of said skirt.
